[57] **CLAIM**

The ornamental design for a riser for letter tray, as shown and described.

DESCRIPTION

FIG. 1 is a left front perspective view of a riser for letter tray showing my new design;
 FIG. 2 is a front elevational view thereof;
 FIG. 3 is a top plan view thereof;
 FIG. 4 is a right side elevational view thereof; the left side elevational view being a mirror image;
 FIG. 5 is a rear elevational view thereof; and,
 FIG. 6 is a bottom plan view thereof.

FIG. 1

FIG. 2

FIG. 3

FIG. 4

FIG. 5

FIG. 6
